UNITED STATES PATENT OFFICE.

JOHN B. SPOWART, OF BERKELEY, CALIFORNIA.

POWER-DRIVEN EARTH AUGER.

Application filed May 23, 1922. Serial No. 563,086.

To all whom it may concern:

Be it known that I, JOHN B. SPOWART, a citizen of the United States, residing at Berkeley, county of Alameda, and State of California, have invented new and useful Improvements in Power-Driven Earth Augers, of which the following is a specification.

This invention relates to a power driven earth auger, and especially to improvements over the structure shown in my copending application entitled "Earth auger," filed July 28, 1920, Serial No. 399,504.

The object of the present invention is to generally improve and simplify boring machines of the character described; to provide a machine which may be readily mounted on the chassis of an ordinary motor truck and so positioned that its operating mechanism may be coupled to the engine shaft or transmission of the truck, thereby enabling the boring operation to be effected by means of power transmitted from the engine; to provide a novel mounting for the boring mechanism whereby if the truck is standing on sloping or otherwise uneven ground, the auger and connected driving mechanism may be adjusted to assume a vertical position, and conversely whereby angular adjustment of the auger may be obtained when angular holes are desired, and further to provide a novel gear transmission and a pair of clutches cooperating therewith whereby the auger may be quickly raised or lowered to boring position and automatically advanced while boring. Other objects will hereinafter appear.

One form which my invention may assume is exemplified in the following description and illustrated in the accompanying drawings, in which—

Fig. 1 is a side elevation of the front end of a motor-truck showing the application of the invention.

Fig. 2 is a plan view thereof.

Fig. 3 is an enlarged plan section taken on line 3—3, Fig. 1.

Fig. 4 is an enlarged vertical, longitudinal section taken on line 4—4, Fig. 2.

Fig. 5 is an enlarged cross section taken on line 5—5, Fig. 4.

Fig. 6 is an enlarged vertical, longitudinal section taken on line 6—6, Fig. 1.

Fig. 7 is an enlarged detail view of the brake band actuating mechanism.

Referring to the drawings in detail, and particularly to Figs. 1 and 2, A indicates the main frame of a motor truck, B the engine, 2 the transmission, 3 an auxiliary transmission, and 4 the front or steering wheels. Suitably secured to one side of the main frame at the forward end thereof is a casing 5, which will hereinafter be termed the bearing casing. Supported by said casing and turnable with relation thereto is an enclosed gear casing 7, and supported by this casing and turnable with relation thereto, as will hereinafter be described, is a transmission case 8, in which is enclosed a set of gears through which power is transmitted to rotate the auger generally indicated at C.

Disposed on one side of the main frame is a sleeve shaft 9, and an internal solid shaft 10, and forming a continuation of said shafts is a sleeve shaft 9^a, see Fig. 3, and an internal solid shaft 10^a. These last named shafts are journaled in a head member 11, which is turnably mounted in the bearing casing 5, the bearings employed being preferably anti-friction bearings as indicated at 12 and 13, respectively. The head member 11 is secured on the end of the bearing casing 5 by means of a ring plate 14, and one side of the head member 11 has teeth formed therein as at 15, which intermesh with a worm pinion 16 journaled in the lower end of the bearing casing, that is the worm pinion is secured on a horizontally disposed shaft extending through the lower part of the bearing casing 5 and one end thereof is provided with a hand wheel 17, whereby rotary movement may be imparted to the shaft and the worm pinion. Such rotary movement is in turn transmitted to the head member 11 through the teeth 15, and its position may thus be adjusted. The gearing casing 7 is rigidly attached to the head member 11 and as such will turn in unison therewith. The transmission case 8, as previously stated, is turnably mounted with relation to the casing 7. This mounting is clearly illustrated at 18, see Fig. 3, that is, the inner face of the case 8 is provided with an annular flange and this is engaged by a ring clamp 19 secured by bolts 20. One side of the flange 18 is provided with teeth, as at 21, see Fig. 1, and these teeth mesh with the worm pinion 22 secured on the shaft 23 journaled in the lower part of the casing 7. This shaft is provided with 110

a hand wheel 24 and when this hand wheel is rotated movement is transmitted to turn the case 8 with relation to the casing 7. In other words universal adjustment of the case 8, which supports the earth auger C, is permitted as two turnable supports are provided, that is these supports are disposed at right angles to each other and universal adjustment may hence be obtained. This is of considerable importance as it permits boring of vertical holes when the truck is standing on sloping or otherwise uneven ground, and it is of further importance as it also permits angular adjustment of the auger when sloping holes are required.

The sleeve shaft 9 and the interior shaft 10 are driven by means of a pair of multiple disk clutches, generally indicated at 24 and 25; shaft 9 being driven by the clutch 24, and shaft 10 by the clutch 25. The driving members of the clutches 24 and 25 are connected as a unit by means of bolts 26 to a sprocket gear 27, which is driven from a main drive shaft 28, through a sprocket pinion 29 and a chain 30, the shaft 28 being in turn driven from the auxiliary transmission 3 by sprocket gears and chain as at 31, or in any other suitable manner desired.

The driving member of the clutch 24 is keyed or splined to the sleeve shaft 9, as at 32, while the driving member of the clutch 25 is keyed or splined to the inner solid shaft 10, as at 33. The clutches are thrown into or out of engagement with their respective driving members by means of cams 34, and these are in turn actuated by cones 35 slidably mounted on the respective shafts 9 and 10; the cones and dogs being of the usual construction and being actuated by manually controlled levers 36 and 37 disposed within convenient reach of the driver's seat. The driving part of each clutch is surrounded by brake bands, as at 38 and 39, and these are in turn thrown into and out of engagement by means of cams 40 actuated by levers 41 directly connected to arms 42, that is both clutches may assume neutral position, driving position or stationary position; neutral position being assumed when the clutches are free and the bands are disengaged; driving position being assumed when the clutches are engaged and the bands are free, and locked or stationary position being assumed when the clutches are free but the bands are tightened to secure the clutches. The sleeve shafts 9 and 9^a and the inner solid shafts 10 and 10^a are disposed in alignment with each other, as shown in Figs. 1, 2 and 6, and a driving connection is formed between the respective shafts as indicated at 43 and 44, respectively; the connection formed between the shafts 10 and 10^a being nothing more or less than a sliding spline, while the connection

43 is a jaw coupling. These couplings to a certain extent form a flexible coupling, and as such automatically take care of any disalignment between the respective shafts.

Secured on the ends of the shafts 9^a and 10^a are bevel pinions, as indicated at 45 and 46, and intermeshing therewith is a pair of bevel gears 47 and 48. The four gears specified are disposed within the gear casing 7; the gears 47 and 48 being secured to the shafts indicated at 49 and 50. These shafts are also disposed within the casing 7 and they are also supported in anti-friction journals, as at 51. The shaft 49 is a sleeve shaft while the shaft 50 is an interior solid shaft. These shafts also have pinions secured on their respective ends, as at 52 and 53, and these pinions intermesh with bevel gears indicated at 54 and 55, said last named gears being disposed within the transmission case 8 and being so disposed as to surround a drive shaft 56 whereby the auger is raised, lowered and rotated. The gear 54 is employed for the purpose of transmitting a rotary movement to the shaft 56, while the gear 55 is employed for the purpose of imparting a vertical movement thereto. This is accomplished in the following manner:

Referring to Fig. 4, it will be noted that gear 54 is secured to or formed as an integral part of a sleeve 57 surrounding the shaft 56. Further by referring to Figs. 3, 4 and 5, it will be noted that splined grooves 58 are formed in the shaft and extend from end to end thereof. The sleeve 57 is keyed or otherwise connected as at 57^a with a lower sleeve 59, in which are journaled rollers 60. The flanges of these rollers enter the splined grooves as shown in Fig. 5, thereby forming a driving connection between the gear 54 and the shaft 56. In actual practice two sets of rollers, such as shown at 60, are employed, one set being disposed above the other, the lowermost set being indicated in dotted lines as at 61, in Fig. 5, while the upper set only is shown in Fig. 4. These rollers are of further importance as they permit a free vertical movement of the shaft when the auger is being raised or lowered and when it is being automatically advanced as will herein-after be described. The sleeve 57 is also extended in an upward direction as shown at 62, and gear 55 is journaled exterior thereof. A sleeve 63 is formed as an integral part of the gear 55, and this sleeve carries a nut 64 which rotates in unison therewith; the nut being in this instance supported by the upper end of the sleeve 62 and being secured to the sleeve 63 by means of clamping nuts 65. The exterior surface of the shaft 56 is threaded or has spiral shaped teeth cut therein, as at 66, and these spiral teeth intermesh with the

nut 64 and as this nut is rotated by the gear 55, an up or down movement may be transmitted to shaft 56 during the operation of the machine.

5 In actual operation it will be understood that the auger C is suitably secured to the lower end of the driving shaft 56. If it is desired to lower the auger rapidly to boring position, it is accomplished by 10 holding the gear 55 stationary and rapidly rotating gear 54; gear 55 being held in a stationary position by locking the clutch 24 through which it is driven. If it is desired to raise the auger rapidly out of the hole, gear 54 is held stationary and gear 55 is rapidly rotated, gear 54 being held stationary by locking the clutch member 25 through which it is rotated. If the auger has been lowered to digging position, and it is desired to automatically advance the same, it may be stated that it is slowly rotated and that it is slowly fed in a downward direction. This is accomplished by rotating the gears 54 and 55 in 15 unison by throwing the respective clutches 24 and 25 in engagement. The pitch and the diameter of the gears 54 and 55 are such that the inner gear 55 will rotate at a slightly slower speed than the exterior or 20 larger gear 54, thus while the two gears rotate in unison, one gear will nevertheless rotate at a slightly greater speed, and as this gear rotates the nut 64, it can be seen that the driving shaft 56 will be slowly 25 fed in a downward direction. If the auger has been raised out of the hole and is clogged with dirt and it is desired to remove the same by centrifugal action, it is possible to rapidly rotate the shaft 56 by 30 speeding up the engine. Both clutches 24 and 25 will in that case be thrown into engagement and the operation will be the same as when digging position is assumed.

The gears 54 and 55 are the final driving 35 gears and the transmission of power from the engine to said gears can be readily traced by referring to Figs. 1, 3 and 6. For instance power is transmitted to shaft 10 when the clutch 25 is engaged; power 40 being transmitted to the clutch through the sprocket gears 27 and chain 30 to the shaft 28, which in turn is driven from the engine through the auxiliary transmission 3 and the chain drive 31. With the shaft 45 10 rotating, power will be transmitted through the splined connection 44 to shaft 10^a. It is then transmitted through the gears 45 and 48 to shaft 49, and through the pinion 53 to the inner gear 54. Similarly, power is transmitted through clutch 50 55 when this is engaged and sleeve shaft 9 to sleeve shaft 9^a through the jaw coupling 43. It is then transmitted through the gears 46 and 47 to the shaft 50, and as 60 this shaft carries and drives the pinion 52,

power will be transmitted to the exterior gear 55. The gears 54 and 55 are driven in unison when the auger is in boring position. They are also driven in unison when it is desired to clean the auger by 70 rapidly rotating the same as the dirt is then thrown off by centrifugal action. Gear 54 is held stationary when it is desired to raise the auger out of the hole and gear 55 is held stationary when it is 75 desired to lower the auger to boring position. These different operations are obtained by swinging the levers 36 and 37, which are within convenient reach of the operator's seat, and it is therefore possible 80 for the operator to drive up to any point where it is desired to bore a hole and then to spot the auger by operating the hand wheels 17 and 24. When the auger has been properly spotted or directed, it is 85 only necessary for the operator to return to his seat and to transmit power to shaft 28. He then operates the levers 36 and 37 and will through these levers control the raising and lowering of the auger, and also 90 throw the clutches into position where the auger is automatically fed in a downward direction when in boring position. The entire mechanism is simple and fairly light 95 in construction and as such may be applied to practically any standard form of motor truck. The positioning of the mechanism at the extreme forward end of the truck permits corners and odd places to be reached, which is a great advantage when 100 it is considered that the machine is employed for the purpose of boring holes for telephone poles, and similarly for boring fence post holes, etc., that is rocks and other obstructions are often encountered 105 and may in this instance be avoided, due to the position of the mechanism with relation to the truck.

While certain features of the present invention are more or less specifically illustrated, I wish it understood that various changes in form and proportion may be resorted to within the scope of the appended claims, similarly that the materials and finish of the several parts employed 110 may be such as the experience and judgment of the manufacturer may dictate or various uses may demand.

In Fig. 4 I have shown the lower collar 59 as bolted to the lower end of the sleeve 120 57, as indicated at 57^a. A spline connection may here be formed, if desired, but the bolts may be preferred as they serve the same purpose and permit ready removal of the lower collar 59. There is no spline 125 connection between the sleeve 57 and the shaft, but the spline connection is formed by the rollers 58 and 61 carried by the collar 59. These rollers therefore form a driving connection and they at the same 130

time permit free vertical movement of the shaft with relation to the collar 59 and sleeve 57.

Having thus described my invention, 5 what I claim and desire to secure by Letters Patent is—

1. In an earth boring machine of the character described, a casing, a shaft extending therethrough, an auger secured to 10 said shaft, a pair of gears within the casing and surrounding the shaft, means for transmitting power from said gears to impart vertical and rotary movement to the shaft, means for rotating the gears in unison and 15 one gear at a greater speed than the other, and means for locking either gear against rotation.

2. In an earth boring machine of the character described, a casing, a shaft extending therethrough, an auger secured to said shaft, a pair of gears within the casing and surrounding the shaft, worm gear teeth formed on the exterior surface of the shaft, 25 a nut engageable with said teeth and adapted to be rotated by one gear, a spline connection formed between the other gear and the shaft to rotate the shaft, means for rotating the gears in unison and one gear at a 30 greater speed than the other, and means for locking either gear against rotation.

3. In an earth boring machine of the character described, a bearing casing, a gear casing carried thereby and turnable with relation thereto, and a transmission case carried 35 by the gear casing and turnable with relation thereto, and said gear casing and transmission case being turnable independently of each other.

4. In an earth boring machine of the character described a bearing casing, a gear casing carried thereby and turnable with relation thereto, and a transmission case carried by the gear casing and turnable with relation thereto, and said gear casing and transmission case being turnable independently of each other, and at right angles to each other to permit universal adjustment.

5. In an earth boring machine of the character described a bearing casing, a gear casing carried thereby and turnable with relation thereto, a transmission case carried by the gear casing and turnable with relation thereto, and said gear casing and transmission case being turnable independently of each other and at right angles to each other to permit universal adjustment, and manually operated means for turning the respective casings, said means also locking the casings against turning movement.

6. In an earth boring machine of the character described a bearing casing, a gear casing carried thereby and turnable with relation thereto, a transmission case carried by the gear casing and turnable with relation

thereto, and said gear casing and transmission case being turnable independently of each other and at right angles to each other to permit universal adjustment, manually operated means for turning the respective casings, said means also locking the casings 65 against turning movement, a shaft extending through the transmission case, and means within said case for imparting a vertical and rotary movement to the shaft.

7. In an earth boring machine of the character described, a bearing case, a head member secured at one end thereof and turnable about a central axis, a gear casing secured to the head member, a transmission case secured to the gear case and turnable 70 about the central axis of the gear case, said head member and the transmission case being turnable at right angles to each other to permit universal adjustment, and manually operated means whereby each casing may be 75 turned independently of the other.

8. In an earth boring machine of the character described, a bearing case, a head member secured at one end thereof and turnable about a central axis, a gear casing secured to the head member, a transmission case secured to the gear case and turnable 80 about the central axis of the gear case, said head member and the transmission case being turnable at right angles to each other to 85 permit universal adjustment, a sleeve shaft and an interior solid shaft journalled in the head member, means for transmitting power to either shaft or to both in unison, a sleeve shaft and an internal solid shaft journalled 90 in the gear casing, bevel gears connecting the sleeve shafts, bevel gears connecting the interior solid shafts, a pair of gears disposed in the transmission case, pinion gears secured on the last named sleeve and interior 95 solid shaft intermeshing with the gears in the transmission case, a shaft passing through the transmission case and the gears contained therein, and means for transmitting vertical and rotary movement to said 100 shaft from the two gears through which it passes.

9. In an earth boring machine of the character described, a bearing casing, a gear casing carried thereby and turnable with relation thereto, a transmission case carried by the gear casing and turnable with relation to said gear casing, said gear casing and transmission casing being turnable independently 115 of each other, a shaft extending through the transmission case, an auger carried by said shaft, and means for transmitting power 120 through the bearing case, the gear case and the transmission case to rotate and elevate the last named shaft and the auger carried 125 thereby.

JOHN B. SPOWART.
